US0D1082314S

(12) **United States Design Patent** (10) **Patent No.:** **US D1,082,314 S**
(45) **Date of Patent:** **** Jul. 8, 2025**

(54) **CASE**

(71) Applicant: **The Noco Company**, Glenwillow, OH (US)

(72) Inventors: **Derek Michael Underhill**, Tempe, AZ (US); **Jonathan Lewis Nook**, Gates Mills, OH (US)

(73) Assignee: **The Noco Company**, Glenwillow, OH (US)

(**) Term: **15 Years**

(21) Appl. No.: **29/889,930**

(22) Filed: **Apr. 18, 2023**

Related U.S. Application Data

(63) Continuation of application No. 29/761,163, filed on Dec. 7, 2020, now Pat. No. Des. 986,595.

(51) **LOC (15) Cl.** **03-01**

(52) **U.S. Cl.**

USPC **D3/301**

(58) **Field of Classification Search**

USPC D3/207, 212, 273, 276, 294, 301, 302

CPC A45C 2011/001

(57) **CLAIM**

The ornamental design for a case, as shown and described.

DESCRIPTION

FIG. 1 is a perspective view of a new design for a case, in a closed position;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a top plan view thereof;

FIG. 8 is a perspective view of a new design for a case, in an open position;

FIG. 9 is a top plan view thereof;

FIG. 10 is a front elevational view thereof; and,

FIG. 11 is a left side elevational view thereof.

The broken lines represent stitching on the case that forms no part of the claimed design.

1 Claim, 11 Drawing Sheets
